UNITED STATES PATENT OFFICE.

JEAN F. WEBB, SR., OF NEW YORK, N. Y.

PNEUMATIC DRAFT GEAR.

Application filed September 1, 1921. Serial No. 497,592.

To all whom it may concern:

Be it known that I, JEAN F. WEBB, Sr., a citizen of the United States, residing at New York, in the county of New York and State of New York, have invented a new and useful Improvement in Pneumatic Draft Gears, of which the following is a specification.

My invention has for its object to provide a draft gear for railway cars and the like whereby the jolts and jars of a train may be cushioned and reduced, if not entirely eliminated, and to provide a yielding or flexible cushion of compressed and confined air to receive the initial blow or impact of metal to metal couplers coming together with terrific force, either in coupling or when trains are in motion, thereby preventing draft gears being broken or pulled out with careless switching or sudden jerks, when long trains are in motion.

In carrying out my invention, I utilize the compressed air of the air brake system to provide the cushioning means in an air tight telescoping cylinder in combination with the cushioning springs housed in the cylinder and formed as a part of the draft gear.

Another object of the invention is to provide means whereby mashing or undue compression of the draft gear springs is prevented or, in other words, to provide means whereby when unusual force is applied to compress the draft springs, the solid abutments will limit the compression so as not to go beyond the safe compression factor of the spring.

A further object of the invention is to provide a pneumatic draft gear consisting generally of cushion springs housed in an air tight cylinder or caisson composed of telescoping sections with provisions for maintaining compressed air in the cylinders, the cylinders and springs being so proportioned and related that the initial shock is received by the air cushion within the cylinders and on further compression of the cylinders, the resistance of the springs will be encountered thereby adding to the cushioning resistance step by step, producing a greater resistance on a constantly weakening blow.

In its more detailed nature the invention also resides in those novel features of con-

struction, combination and arrangement of parts, all of which will be first fully described and then be specifically pointed out in the appended claims, reference being had to the accompanying drawings, in which:

Figure 1 is a top plan view of one embodiment of my invention.

Figure 2 is an inverted horizontal section of the same.

Figure 3 is a cross section on the line 3—3 of Figure 1.

Figure 4 is a detail perspective view of the telescopic cylinder and spring unit removed from the yoke.

Figure 5 is a top plan view of another embodiment of the invention.

In the drawings in which like numerals and letters of reference designate like parts in all of the figures, 1 represents the sills of the car which have the fixed abutments 2—2 spaced apart and between which the heads 6—6 of the shock absorbing unit are located. The coupler 3 is provided with the usual yoke 4.

In carrying out my invention according to the embodiment thereof shown in Figures 1 to 4, inclusive, I place between the opposing pairs of abutments 2—2 within the yoke 4, a cushioning unit composed of telescoping cylinders 8—8, each closed at their outer ends by heads 6 which have lugs 7 to rest on the yoke 4, the inner end of the outer cylinder 8 also having lugs 9 to rest on the yoke 4 and thereby sustain the parts against dropping through the yoke and at the same time enabling the unit to be easily removed and replaced for inspection and repair, when necessary. The yoke 4 rides between and is supported by the pairs of abutments 2—2 (see Figure 3). The telescoping cylinders 8—8 where they telescope are provided with packing rings 11 to effect an air tight joint, whereby to maintain air under pressure within the chamber of the cylinders 8—8, the latter being admitted from the train line 15 through the connection 16 and back check valve 17 to the port 14 which communicates with the interior of the cylinders.

10 is a pet cock through which water of condensation may be drained from the cylinders. Within the cylinders is located a

set of compression springs 12, the extended length of which is such that when the cylinder heads 6-6 are separated to their utmost degree, i. e. when they each lie against their respective abutments 2-2, will apply no pressure to the cylinder heads, that is to say the extended length of the springs is less than the distance between the heads 6-6 when such heads are at their extreme outer 10 positions for a purpose presently to appear.

The heads 6-6 are provided with lugs 13 for holding the several springs 12 of the set out of engagement with one another to prevent interlocking of the spring loops.

15 Instead of arranging the unit as shown in Figures 1 to 4, inclusive, where the yoke 4 lies horizontally, the same may be arranged as shown in Figure 5. The heads 6-6 being made of larger diameter than that of the 20 cylinders 8-8, may be grooved at 7^a to receive the yoke 4, it being, of course, understood that in assembling the parts in this form, the yoke is first placed over the unit to lie in the grooves or recesses 7^a before the 25 yoke is riveted to the coupler head 3 and in removing the parts the operation is reversed. In this form also the outer cylinder 8 may be provided with pairs of shoulders 9^a-9^a to engage the sides of the yoke and the cylinder 30 8 and heads 6 may be further provided with lugs 9^b and 7^b to ride in slots in suitable guide plates 1^x secured to the sills 1 in any well known or desirable way and thereby sustain the weight of the parts.

35 The embodiment shown in Figures 1 to 4, inclusive, is the preferred embodiment of the invention as by its use the ready removal and replacement of the cushioning unit can be made.

40 In order to remove the cushioning unit from the yoke in Figure 1, the connection 16 is removed. The heads 6-6 are held toward each other by suitable clamp devices not shown, and the unit (see Figure 4) is lifted 45 up and out from the yoke and from between the abutments 2-2. The unit is replaced by reversing this sequence of operations as will be quite evident to those skilled in the art by mere inspection of Figures 1 and 3 50 of the drawings. It should, of course, be understood that if the unit lies close to the car floor the car floor will be provided with the usual cover plate which can be removed before attempting to remove or replace the 55 cushioning unit as above described.

In the practical operation of my invention, the pressure maintained within the telescoping cylinders 8-8 is the equivalent of the train line air pressure, a suitable back 60 check valve 17 being provided to hold the air pressure in the cylinders and prevent the air escaping back in the train line, if the train line pressure should fall at any time beyond the pressure within the cylinders.

65 The essential feature of the present invention resides in providing a cushioning unit combining an air cushion with mechanical spring action to absorb the shocks and at the same time enclose and protect the springs against the elements and hold them in such 70 position that they will not interlock with each other; it will also be observed that the length of the cylinders 8 is such that upon completely telescoping the cylinders, they assume such position before the safe limit of 75 compression of the springs is reached, thereby protecting the springs against mashing and against such compression as would pass their limit of elasticity. My construction thus prevents crystallization of the springs 80 by over compression of the same and by graduated action of the cushioning means (initiating the cushioning action by compressed air, then continuing it by compressed air resistance plus mechanical spring resistance) I am enabled to increase the life 85 of the springs considerably. It will also be observed that as the cylinders are telescoped the compressed air within the cylinders is further compressed, depending upon the distance to which the cylinders are telescoped, the pressure rising in the cylinders as the cylinders telescope together, thereby increasing the resisting pressure as the cylinders are telescoped, this increase of pressure 90 being augmented by the spring action after the initial blow has been received by the pure air cushion action at the commencement of the telescoping of the cylinder.

95 By utilizing the air pressure of the train line air in the manner stated, ample cushioning resistance per square inch of surface is provided to take care of the blows encountered in practice and while I prefer to utilize the train line air, yet it is obvious that a separate source of air supply may be provided for the cylinders 8-8 if found desirable.

100 By making the cylinders 8-8 air tight, it is also possible to supply the same with a 110 quantity of lubricant to keep the packing rings 11 in condition to effect an air tight seal.

115 From the foregoing description taken in connection with the accompanying drawings, the complete construction, operation and advantages of the invention will be clearly understood by those skilled in the art.

What I claim is:

1. In a draft gear, the combination with the front and rear fixed pairs of sill abutments, the coupler head and the yoke which rides between and is supported by the said abutments; a cushioning unit bodily insertable from above into the yoke in its assembled condition and removable in the same way therefrom.

120 2. In a draft gear, the combination with the front and rear fixed pairs of sill abutments, the coupler head and the yoke which 125

rides between and is supported by the said abutments; a cushioning unit bodily insertable from above into the yoke in its assembled condition and removable in the same way therefrom, said unit comprising telescoping cylinder sections having portions to abut on the top of said yoke and support the unit thereon, all being arranged whereby the unit in its assembled condition may be inserted 10 bodily into and removed from the yoke and when in place will be held down by gravity.

JEAN F. WEBB, Sr.
